A. L. BOYER

LOOSE LEAF BINDER

Filed March 8, 1926

FIG. 3.

Inventor

A. L. Boyer.

By

Lacy & Lacy, Attorneys

UNITED STATES PATENT OFFICE.

ALBERT L. BOYER, OF MARION, INDIANA.

LOOSE-LEAF BINDER.

Application filed March 8, 1926. Serial No. 93,330.

This invention relates to loose leaf binders and one object of the invention is to provide the binder with improved leaf-engaging rings so secured to a mounting strip that they will be rigidly connected therewith.

Another object of the invention is to so form the leaf-engaging rings that the leaves may be readily engaged with the rings and turned without catching against the open ends of the rings.

Another object of the invention is to so mount the ring-carrying strip that it may be detached from the back of the binder.

This invention is illustrated in the accompanying drawing, wherein—

Figure 1 is a perspective view of the improved loose leaf binder;

Fig. 2 is a fragmentary sectional view taken on the line 2—2 of Fig. 1 with the leaves omitted;

Fig. 3 is a top plan view of one of the leaf-engaging rings and a fragment of its mounting strip;

Fig. 4 is a view similar to Fig. 2 illustrating a modified construction, and

Fig. 5 is a bottom plan view illustrating a further modified construction.

The body portion of the binder is preferably formed of soft leather and is creased to form the back 1 and front and rear cover sheets 2 and 3 which are of greater length and width than the sheets of paper 4 to be received in the binder. A strip 5 which is formed of sheet metal and of less length and width than the back 1 of the binder is disposed longitudinally of the back and formed adjacent its ends with openings 6 adapted to receive fasteners 7 by means of which the strip 5 is secured to the back.

The fasteners may be of any conventional construction but in the preferred form are constructed, as shown in Fig. 2. Referring to this figure, it will be seen that each of the fasteners includes a head 8 adapted for

flat contacting engagement with the outer face of the back 1 and arms or prongs 9 which are passed through the back and strip 5 and bent to extend in overlying engagement with the outer face of the strip. These

fasteners may be easily put in place and when clinched, as shown in Fig. 2, they will firmly hold the strip 5 in engagement with the back 1 but permit the strip to be easily removed when desired. It will, therefore,

be seen that the binders before being sold 55 may have the backs kept in a stack upon a shelf and the strips 5 and rings carried thereby stored in a box or other convenient receptacle where they will be out of the way and take up a minimum amount of space. 60 It will also be evident that if so desired additional strips 5 may be purchased so that when a record of transactions has been kept for a given length of time the sheets of paper together with the strip 5 and paper-engaging 65 rings may be removed from a binder and filed away as a permanent record and a new strip and sheets of paper mounted in the binder.

The sheets of paper are formed with openings 10 near one side edge, and these openings are adapted to receive the rings 11 which are rigidly secured to the strip 5 transversely thereof. The rings may be spot welded to the strip 5, as shown at 12 75 in Fig. 2, or a hollow rivet 13 may be welded to each ring, as shown in Fig. 4, and the stem 14 of the rivet passed through an opening formed in the strip 5 and clinched against the inner face of the strip. The 80 rings are split rings, and referring to Fig. 3 it will be seen that in forming the split rings each is cut diagonally and the separated end portions of the ring offset transversely of each other so that the diagonally extending end faces 15 of the ring are partially overlapped. By having the separated end portions offset and in partially overlapped relation to each other, a sheet of paper when turned will move from one end portion of 85 the ring onto its other end portion and, since it will contact with the diagonally extending end face of the second end portion of the ring, it will not catch upon the pointed end of the second end portion of the ring 90 and become torn. Therefore, the sheets may be freely turned without danger of becoming torn loose from the rings.

If the binder is formed with a back having sufficient stiffness to retain a rivet, the strip 5 may be omitted and rings, such as shown in Fig. 5, employed. The ring shown in this figure and indicated in general by the numeral 16 is of the same construction shown in Fig. 4, except that the rivet 13 is omitted and the ring is to be secured directly to the back by a hollow or solid rivet or other suitable fastener passed through an opening

17 formed in the widened and flattened portion 18 which constitutes a base for the ring.

Having thus described the invention, I claim:

- 5 1. In a loose leaf binder, a mounting strip adapted to be secured upon a carrier, a mounting strip extending longitudinally of said back and secured thereto, and leaf-engaging rings secured to said strip transversely thereof and each formed with a diagonally extending slit to provide the ring with separated end portions having diagonally disposed end faces, the said end portions being offset transversely of each other with their end faces only partially overlapped.

2. In a loose leaf binder, a leaf-engaging ring formed with a diagonally extending slit providing separated ends for the ring, the said ends being offset transversely of the 20 ring.

3. In a loose leaf binder, a leaf-engaging ring formed with a diagonally extending slit to provide the ring with separated end portions having diagonally extending end faces, the said end portions being offset transversely of the ring and having their end faces disposed in only partial overlapped relation to each other.

In testimony whereof I affix my signature.

ALBERT L. BOYER. [L. S.]
